RECORD-CARD HOLDER

George D. Wiegert, New Haven, Conn., assignor
to The Merriam Manufacturing Company, Dur-
ham, Conn., a corporation of Connecticut

Application May 23, 1944, Serial No. 536,953

5 Claims. (Cl. 206—40.6)

The present invention relates to improvements in card-holders and relates more particularly to improvements in holders which are adapted for the reception of record-cards such, for instance, as cards for keeping track of production operations in manufacturing plants, though the card-holders are available for other uses.

One of the objects of the present invention is to provide a superior record-card holder so constructed and arranged as to conveniently hold record-cards and to shield the same against mechanical injury, to thereby enable the card-holder with its set of record-cards, to accompany items of manufacture through various steps of manufacture to completion.

Another object of the present invention is to provide a superior record-card holder so constructed and arranged as to provide means whereby the contained record-cards may be conveniently divided into sections.

A further object of the present invention is to provide a superior record-card holder constructed and arranged so that record-cards may be divided into sections, and one or more such sections may be retained in the holder with provision for displacing such section from its original location into a noninterfering location, with respect to other complete record-cards still remaining in the holder.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is an end view of a record-card holder constructed in accordance with the present invention, and showing a group of record-cards mounted therein;

Fig. 2 is a face view thereof;

Fig. 3 is an edge view thereof;

Fig. 4 is a longitudinal sectional view taken on the line 4—4 of Fig. 2 and showing the right-hand portion of the uppermost record-card as being lifted into engagement with the tear-off bar, preparatory to being detached;

Fig. 5 is a face view corresponding to Fig. 2 but showing the condition of the uppermost card after the right-hand part thereof has been detached, and the left-hand part thereof has been swung into position over the tear-off lip, preparatory to having its outer-portion detached;

Fig. 6 is a sectional view taken on the line 6—6 55 the operation covered thereby is completed, while

of Fig. 5 and showing, by broken lines, the outer-portion of the left-hand part of the record-card bent downwardly preparatory to being severed;

Fig. 7 is a face view of the four sections of a record-card of the type shown in the preceding figures; and

Fig. 8 is a perspective view of the record-card holder stripped of record-cards.

The particular form of the present invention shown in the accompanying drawings includes a substantially-rectangular body member 10 which may be conveniently formed from sheet metal, and which is bent up along its respective opposite longer edges to form guard-flanges 11 and 12. 10 15 Spot-welded or otherwise secured to the upper-surface of the upper left-hand portion of the body-member 10, is an L-shaped retaining-member generally designated by the reference character 13 and including an upstanding retaining-flange 14 and a base-portion 15, which latter is spot-welded or otherwise secured directly to the upper-face of the body-member 10.

Substantially midway of its length, the body-member 10 is provided with a tear-off bar 16 25 having flanges 17 and 18 at its respective opposite ends which are respectively spot-welded or otherwise secured to the respective inner-faces of the guard-flanges 11 and 12 of the said body-member 10. The lower or back edge of the tear-off bar 16 is spaced upwardly with respect to the upper-face of the main-portion of the body-member 10, so as to provide a space for the accommodation of a plurality of record-cards generally designated by the reference character 19.

30 In the instance shown, each of the record-cards 19 is provided with a vertical line of perforations or piercings 20 and a horizontal line of perforations or piercings 21. The said lines of perforations or piercings 20 and 21 or their equivalent, 35 constitute lines of weakness along which a given record-card 19 may be torn.

The aforesaid lines of perforations 20 and 21 serve to potentially divide a given record-card 19 into four sections respectively designated by the 40 reference characters 22, 23, 24 and 25. The upper left-hand section 22 may constitute the section which remains in the card-holder along with the similar sections of companion cards, until the manufacture of the item is completed, while the 45 lower left-hand section 23 may be torn off and transferred to a production chart as rapidly as the given operation is completed. The upper right-hand section 24 of a given card may be transmitted to the payroll department as soon as 50 the operation covered thereby is completed, while

the lower right-hand section 25 of a given card may be kept in the possession of the worker as a record to check the worker's own pay when such pay is received.

Adjacent the upper left-hand corner of the upper left-hand section 22 of each card, the body-member 10 of the card-holder is formed with a perforation 26 (Fig. 8) to provide means for pivotally attaching a group of record-cards such as 19. In the instance shown, an ordinary double-armed flexible fastener 27 is extended downwardly through the upper left-hand portion of the upper left-hand sections 22 of the record-cards of the group or pile thereof, and the arms of the said fastener are bent over against the back-face of the body-member 10. In this manner, the record-cards are secured in place in the body-member 10, and provision is made whereby the entire left-hand portion constituting the sections 22 and 23, may be pivoted from the position shown in Fig. 2 to the position shown in Fig. 5, for purposes as will hereinafter appear.

When the given operation set forth on the uppermost record-card 19 is completed, the worker may detach the right-hand portion of the said record-card (consisting of the sections 24 and 25) by lifting the free end of the given record-card to thus bring the portion thereof adjacent the perforations 20 against the under-edge of the tear-off bar 16, as is shown in Fig. 4. Now, since the vertical line of perforations 20 is located adjacent the edge of the said tear-off bar, the part of the record-card consisting of the sections 24 and 25 may be jointly detached from the part consisting of the sections 22 and 23. The now-detached right-hand portion of the record-card (consisting of the sections 24 and 25) may now be parted along the horizontal line of perforations 21, whereupon the upper section 24 may be sent to the payroll department and the lower section 25 retained by the worker as a receipt.

After the joint severance of the sections 24 and 25 as above described, the remaining left-hand portion of the record-card (consisting of the sections 22 and 23) may be pivoted about the fastener 27 and swung into the position in which it is shown in Figs. 5 and 6. In this manner, the line of perforations 21 will be brought into registry with the tear-off lip 28 constituted by the left-edge of the retaining-member 13. Now, by bending the section 23 downwardly as indicated by broken lines in Fig. 6, the said section 23 may be detached from the section 22. The detached section 23 may now be dispatched for insertion in the production chart, while the section 22 will be retained in the record-card holder by the fastener 27, but in a position of noninterference with the second card of the series, which will thus be exposed, so that the information contained thereon will be available to the worker and supervisor.

The completion of the second operation will be the occasion for repeating the severing or detaching operation above described in connection with the topmost record-card, and so on sequentially through the series of record cards.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A record-card holder, including in combination: a body provided intermediate its respective opposite ends with pivot-means for pivotally-attaching record-cards to the said body, the said body being provided with two separate substantially-parallel tear-off means respectively located on the opposite sides of the said pivot-means in position to be engaged by a portion of a card to facilitate the tearing-off of a portion thereof, one of the said tear-off means being spaced above the upper-face of the said body to provide space for the accommodation of record-cards.

2. A record-card holder, including in combination: a body provided intermediate its respective opposite ends with pivot-means for pivotally-attaching record-cards to the said body, the said body being provided with two separate substantially-parallel tear-off means respectively located on the opposite sides of the said pivot-means in position to be engaged by a portion of a card to facilitate the tearing-off of a portion thereof, one of the said tear-off means comprising a tear-off bar having its lower-face spaced above the upper-face of the said body to provide space for the accommodation of record-cards.

3. A record-card holder, including in combination: a body provided intermediate its respective opposite ends with pivot-means for pivotally-attaching record-cards to the said body, the said body being provided on one side of its said pivot-means with a first tear-off means and being provided on the other side of the said pivot-means with a second tear-off means extending in substantial parallelism with the said first tear-off means, the said second tear-off means being spaced upwardly with respect to the upper-face of the said body to provide space for the accommodation of record-cards; and vertically-extending retaining-means positioned adjacent the said first tear-off means to retain portions of a card in a position adjacent the said first tear-off means.

4. A record-card holder, including in combination: a body of substantially-rectangular form and provided adjacent one of its corners with means for pivoting record-cards, the said body provided at one end with a tear-off lip adjacent the said pivoting-means; a tear-off bar extending crosswise of the said body in substantial parallelism with the said tear-off lip and located on the opposite side of the said pivoting-means therefrom, the lower-face of the said tear-off bar being spaced above the upper-face of the portion of the said body to provide space for the accommodation of record-cards.

5. A record-card holder, including in combination: a body having one of two complementary substantially-parallel guard-flanges projecting along each of its opposite edges to form a trough-like structure; a tear-off bar extending crosswise of the said body between the two said guard-flanges thereof, the lower-face of the said tear-off bar being spaced above the upper-face of the portion of the said body lying between the two said guard-flanges to provide space for the accommodation of record-cards; a tear-off lip on said body extending in substantial parallelism with the said tear-off bar; and pivot-means located intermediate the said tear-off lip and the said tear-off bar and providing means for pivotally-attaching record-cards to the said body.
